EJECTOR TYPE REFRIGERATING SYSTEM

Leo B. Miller, Bronxville, N. Y., and Henry F. Dever, Minneapolis, Minn., assignors to Minneapolis-Honeywell Regulator Company, Minneapolis, Minn., a corporation of Delaware

Original application September 10, 1934, Serial No. 743,408. Divided and this application November 20, 1935, Serial No. 50,690

14 Claims. (Cl. 62—2)

This invention relates to refrigerating systems or cooling systems, utilizing a steam jet ejector for performing the cooling action. This application is a division of our copending application Ser. No. 743,408, filed September 10, 1934, which has matured into Patent 2,143,356, dated January 10, 1939.

It is an object of this invention to provide a control system for a steam jet ejector refrigerating mechanism whereby the operation of the refrigerating mechanism is accurately controlled and whereby the operation thereof is maintained safe at all times.

It is an object of this invention to provide a control system for a steam jet ejector refrigerator mechanism wherein the ejector is controlled in accordance with steam pressures and condenser vacuum.

Another object of this invention is to provide a control system for a refrigerating mechanism of the class described wherein the boiler for supplying steam to the refrigerating mechanism is placed in operation in response to changes in the condition to be controlled and in response to the chilled water or evaporator temperature and wherein the ejector is placed in operation in response to the steam pressure developed by the boiler and the vacuum in the condenser.

Still another object of this invention is to provide a control system for a steam jet ejector refrigerating mechanism wherein the boiler for supplying steam to the refrigerating mechanism is placed in operation in response to a demand for cooling and the chilled water temperature, wherein in the secondary ejectors and the vacuum pump are placed in operation when the boiler steam pressure rises to a predetermined value and wherein the primary ejector is placed in operation when a predetermined vacuum has been produced in the condensers and when the boiler steam pressure has reached a predetermined higher value.

Other objects and advantages will become apparent to those skilled in the art upon reference to the accompanying specification, claims and drawing, in which drawing is diagrammatically illustrated our invention as applied to a steam jet ejector refrigerating mechanism.

An evaporator wherein the cooling fluid is cooled is designated at 10. Cooling fluid which may take the form of chilled water is drawn from the evaporator 10 through a pipe 11 by a circulating pump 12. The chilled water is then circulated through a cooling coil 13 which may be located in a conditioning chamber 14 and conveyed

by a pipe 15 to a spray 16 located within the evaporator 10. A vacuum is maintained in the evaporator 10 by means of a primary ejector 17 which connects into a primary condenser 18. The secondary condenser 20 is provided with secondary ejectors 21 and 22 for assisting in the production of a vacuum in the condensers 18 and 20 and for purging air and other non-condensable gases from the condensers 18 and 20.

The primary ejector 17 is provided with steam through a pipe 23 connected into a steam header 24 which in turn connects into a boiler 25. The flow of steam through the pipe 23 to the primary ejector 17 is controlled by means of a primary steam valve 26 which is moved to an open or closed position by means of a motor means 27. Steam is supplied to the secondary ejectors 21 and 22 by means of pipes 28 and 29 connecting into the pipe 23 ahead of primary steam valve 26. The supply of steam to the secondary ejectors 21 and 22 is controlled by a secondary steam valve 30 which is moved to an open or closed position by means of a motor means 31.

Condensed steam is drawn from the condenser 18 through a pipe 19 by means of a vacuum pump 33. A suitable drain or outlet for exhausting the secondary condenser, is indicated by the reference character 34. The vacuum pump 33 returns the condensate to the boiler 25. For purposes of illustration in this application, the boiler is shown to be of the gas-fired type, the gas being supplied to the boiler through a gas pipe 35 under the control of a gas valve 36 which is moved to open or closed position by means of a motor means 37.

Condensing fluid is conveyed from some source, not shown, through a pipe 39 to the primary condenser 18 under the control of a valve 40 which is moved to open or closed position by means of a motor 41. The used condensing fluid is conveyed away from the primary condenser 18 through a pipe 42. The secondary condenser 20 is connected by pipes 43 and 44 with the condensing water pipes 39 and 42, respectively, whereby condensing fluid is supplied likewise to the secondary condenser 20 when the valve 40 is moved to an open position. In case a cooling tower is utilized for cooling the condensing fluid, the pipes 39 and 42 may extend to a cooling tower, not shown, and under such circumstances, it is desirable to have forced circulation of the condensing fluid. The circulating pump, not shown, may be placed in the pipe 39 and the arrangement may be such that when the valve 40 is open, the circulating pump is placed in operation.

A control device, responsive to the condition to be controlled, is designated generally at 46 and for purposes of illustration in this application, it is shown to comprise a thermostatic element 5 47 for operating a switch arm 48 with respect to a contact 49, the arrangement being such that upon an increase in temperature affecting the bimetallic element 47, the switch arm 48 is moved in the direction of the arrow indicated by H into 10 engagement with the contact 49. Preferably, such engagement is made when the temperature increases to 75° F.

A low limit control is generally designated at 15 50 and may comprise a bellows 51 connected by a pipe 52 to the steam header 24. The bellows 51 operates a pivoted lever 53 which carries a mercury switch 54, the arrangement being such that when the boiler pressure decreases to 2 pounds, the mercury switch 54 is moved to a circuit 20 making position as shown in the drawing. This invention also contemplates the use of a high limit control generally designated at 55 and which may comprise a bellows 56 connected by a pipe 57 to the steam header 24. The bellows 56 25 operates a pivoted lever 58 which carries a mercury switch 59, the arrangement being such that when the boiler pressure increases to 14 lbs., the mercury switch 59 is tilted to a circuit breaking position.

30 A pressure responsive device generally designated at 60 may comprise a bellows 61 connected by a pipe 62 to the steam header 24. This bellows 61 may operate a pivoted lever 63 which carries a double-ended mercury switch 64. 35 Upon an increase in boiler pressure to 9 lbs., the mercury switch 64 is tilted to a position opposite to that shown in the drawing to make contact between the left contacts thereof. When the pressure in the boiler 25 decreases to 7 lbs., the 40 mercury switch is returned to the position shown in the drawing to make contact between the right-hand contacts. The pressure responsive device 60 is adapted to control the energization of a relay coil 65, the arrangement being such 45 that when the relay coil 65 is energized, a switch arm 66 is moved into engagement with contact 67.

The boiler 25 is provided with a low water cut-off mechanism generally designated at 68 which 50 is adapted to operate a mercury switch 69 to a circuit-breaking position when the level of the boiler water becomes abnormally low. A vacuum responsive device is designated generally at 70 and comprises a bellows 71 connected by a 55 pipe 72 into the secondary condenser 20. The bellows 71 operates a pivoted lever 73 which carries a double-ended mercury switch 74, the arrangement being such that when the vacuum in the secondary condenser 20 reaches 16 inches 60 of mercury, the switch is tilted from the position shown in the drawing to a position wherein contact is made between the right contacts thereof. Another pressure-responsive device is generally designated at 75 and comprises a bellows 76 connected into the steam pipe 23 by means of a pipe 77. The bellows 76 operates a pivoted lever 78 which carries a double-ended mercury switch 79. When the boiler pressure increases to 12 lbs., the mercury switch 79 is tilted to a position opposite 70 that shown in the drawing to make contact between the left contacts and when the boiler pressure decreases to 11 lbs., the mercury switch is returned to the position shown in the drawing to make contact between the right contacts.

75 A temperature responsive device is generally

designated at 80 and comprises a bellows 81 connected by a capillary tube 82 to a bulb 83 located within the evaporator 10. The bellows 81 is adapted to operate a lever 84 which carries a single-ended mercury switch 85. Upon a decrease in evaporator or chilled water temperature to a value of say, 35° F., the mercury switch 85 is moved to a circuit-breaking position. 5

This invention contemplates the use of a relay coil 86 which when energized moves a switch 10 arm 87 into engagement with a contact 88. Line wires for supplying power to the control system of our invention are designated at 90 and 91.

When the boiler pressure decreases to 2 lbs. so as to move the mercury switch 54 to a circuit-making position, a circuit is completed from the line wire 90 through wires 92 and 93, mercury switch 54 of the low limit control 50, wires 97 and 98, mercury switch 69 of the low water cut off 68, wire 99, mercury switch 85 of the evaporator temperature responsive device 80, wire 100, motor 31, and wire 101 back to the other line wire 91. Completion of this circuit causes energization of the motor 37 and consequent opening of the gas valve 36 whereby the boiler 25 is energized to generate steam. When the steam pressure has been restored to 2 lbs., the mercury switch 54 is moved to a circuit-breaking position to break the above circuit to close the valve 36 to prevent the further generation of steam. In 30 this manner, steam at 2 lbs., may be maintained within the boiler 25. Since the low water cut-off mechanism is included in this circuit, the boiler 25 may not be energized if the boiler water is abnormally low. Also, if the evaporator temperature is down to 35° whereby further cooling is not needed, operation of the boiler 25 is prevented since the mercury switch 85 included in the above-referred to circuit is moved to a circuit breaking position upon the occurrence of a 40 35° temperature value within the evaporator 10. In this manner, we have provided a low limit control for the boiler 25 but if such low limit control is not desired, the pressure switch 50 may be eliminated. 45

Upon a call for cooling, the switch arm 48 is moved into engagement with the contact 49 to complete a circuit from the line wire 90 through wires 92 and 102, bimetallic element 47, switch arm 48, contact 49, wire 103, mercury switch 59 50 of the high limit control 55, wires 104 and 98, mercury switch 69 of the low water cut off device 68, wire 99, mercury switch 85 of the evaporator temperature responsive device 80, wire 100, valve motor 37 and wire 101 back to the other line 55 wire 91. Therefore upon a call for cooling, the valve motor 37 is energized to open the gas valve 36 to cause operation of the boiler 25 to generate steam therein. Since the above-referred to circuit includes the high limit control 55 which is 60 moved to a circuit-breaking position upon the occurrence of 14 lbs. steam pressure within the boiler 25, the occurrence of dangerous pressures within the boiler 25 is prevented. Likewise, the valve 36 is prevented from being opened when the 65 boiler water level is abnormally low or when the evaporator temperature is abnormally low by means of the low water cut-off device 68 and the evaporator temperature responsive device 80. In this manner, safe operation of the boiler 25 is insured. 70

When the boiler pressure has increased to 9 lbs., due to the operation of the boiler in the above-referred to manner, the mercury switch 64 of the pressure responsive device 60 is moved to 75

a position opposite to that shown in the drawing to complete a circuit from the line wire 90 through wire 106, left contacts of mercury switch 64, wires 107, 108 and 109, secondary valve motor 31 and wires 110 and 111 back to the other line wire 91. Completion of this circuit causes opening of the valve 30 to supply steam to the secondary ejectors 21 and 22. When the boiler pressure decreases to a value lower than 9 lbs., say 7 lbs., the mercury switch 64 is returned to the position shown in the drawing to complete a circuit from the line wire 90, through wire 106, right contacts of mercury switch 64, wires 112 and 113, the secondary valve motor 31 and wires 110 and 111 back to the other line wire 91. Completion of this circuit causes operation of the valve motor 31 to move the valve 30 to a closed position to prevent the further supply of steam to the secondary ejectors 21 and 22. In this manner, the secondary ejectors 21 and 22 are controlled directly in response to a predetermined boiler steam pressure.

Movement of mercury switch 64 to the position opposite to that shown in the drawing completes a circuit also from the line wire 90, through wire 106, mercury switch 64, wires 107 and 114, relay coil 65 and wire 115 back to the other line wire 91. Completion of this circuit at 9 lbs. steam pressure causes energization of the relay coil 65 to move the switch arm 66 into engagement with the contact 67. Movement of switch arm 66 into engagement with the contact 67 completes a circuit from the line wire 90, through wire 116, contact 67, switch arm 66, wire 117, electrically operated vacuum pump 33 and wire 118 back to the other line wire 91. Completion of this circuit causes operation of the electrically operated vacuum pump 33 which combines its action with that of the secondary ejectors 21 and 22 to produce a vacuum in the primary and secondary condensers 18 and 20. When the boiler pressure decreases below 9 lbs., the circuit through the relay coil 85 is broken and the relay coil 65 is therefore deenergized to move the switch arm 66 out of engagement with the contact 67 to prevent the further operation of the vacuum pump 33.

Movement of the mercury switch 64 by the occurrence of 9 lbs. steam pressure to a position opposite to that shown in the drawing completes another circuit from the line wire 90, through wire 106, mercury switch 64, wires 107, 108 and 109, valve motor 41 and wires 120 and 111 back to the other line wire 91. Completion of this circuit causes operation of the valve motor 41 to move the valve 40 to an open position whereby condensing fluid is delivered to the primary and secondary condensers 18 and 20. When the boiler steam pressure drops below 9 lbs., a circuit is completed from the line wire 90, through wire 106, mercury switch 64, wires 112 and 121, valve motor 41 and wires 120 and 111 back to the other line wire 91. Completion of this circuit causes operation of the valve motor 41 to move the valve 40 to a closed position to prevent the further supply of condensing fluid to the primary and secondary condensers 18 and 20. In case a circulating pump is used, the pump may be placed in operation in the same manner that the valve 40 is opened, that is, the pump may be placed in operation when the steam pressure rises above 9 lbs., and may be placed out of operation when the steam pressure drops below 9 lbs.

From the above it is seen that when the boiler pressure reaches a predetermined value illustrated as 9 lbs., the secondary ejectors 21 and 22,

the vacuum pump 33 is placed in operation and the valve 40 is opened to supply condensing water to the primary and secondary condensers 18 and 20. When the boiler pressure decreases below this predetermined value, to say 7 lbs., as illustrated, the secondary steam valve 30 is closed to prevent the further operation of the secondary ejectors 21 and 22, the vacuum pump 33 is stopped and the valve 40 is closed to prevent the further circulation of condensing fluid through the condensers 18 and 20.

When a predetermined vacuum has been produced in the condensers 18 and 20 by the action of the secondary ejectors 21 and 22 and the vacuum pump 33, the mercury switch 74 of the vacuum responsive device 70 is moved to a position opposite that shown in the drawing. Tilting of the mercury switch in this manner is preferably made at a vacuum of 16 inches of mercury. When the boiler steam pressure rises to a predetermined higher value, say 12 lbs., the mercury switch 79 of the pressure responsive device 75 is tilted to a position opposite to that shown in the drawing. Tilting of the mercury switches 74 and 79 in this manner in response to a predetermined high boiler pressure and a predetermined vacuum within the condensers 18 and 20 completes a circuit from the line wire 90, through wires 123 and 124, mercury switch 74, wire 125, mercury switch 79, wires 126 and 127, primary valve motor 27 and wire 128 back to the other line wire 91. Completion of this circuit causes operation of the valve motor 27 to open the valve 26 to supply steam to the primary ejector 17.

If the vacuum in the secondary condenser 20 should fall below 16 inches of mercury, the mercury switch 74 is returned to the position shown in the drawing to break the above-referred to circuit and to complete a circuit from the line wire 90, through wires 123 and 124, mercury switch 74, wires 129 and 130, primary valve motor 27 and wire 128 back to the other line wire 91. Completion of this circuit causes operation of the valve motor 27 to move the valve 26 to a closed position to prevent the further supply of steam to the primary ejector 17. In a like manner, if the steam pressure should fall below 12 lbs., so as to tilt the mercury switch 79 to the position shown in the drawing, a circuit is completed from the line wire 90, through wires 123 and 131, mercury switch 79, wires 132 and 130, valve motor 27 and wire 128 back to the other line wire 91. Completion of this circuit causes operation of the valve motor 27 to move the valve 26 to a closed position. Therefore, it is seen that the primary ejector 17 is placed in operation only when there is sufficient steam pressure to insure the proper operation thereof and when there is a predetermined vacuum existing within the condensers 18 and 20. Therefore, the primary ejector 17 is not allowed to operate if unfavorable conditions are present which would prevent the satisfactory operation thereof.

Movement of switches 74 and 79 to the positions opposite to those shown upon the occurrence of a predetermined vacuum and a predetermined steam pressure also causes completion of a circuit from the line wire 90, through wires 123 and 124, mercury switch 74, wire 125, mercury switch 79, wires 126 and 134, relay coil 86 and wires 135 and 128 back to the other line wire 91. Completion of this circuit causes energization of relay coil 86 to move the switch arm 87 into engagement with the contact 88. This causes completion of a circuit from the line wire 90, through

wire 136, contact 88, switch arm 87, wire 137, electrically operated circulating pump 12 for the chilled water and wire 138 back to the other line wire 91. This causes operation of the circulating pump 12 to supply chilled water to the cooling coil 13 located in the conditioning unit 14. If either of mercury switches 74 or 79 are moved to the position shown in the drawing as the result of a decrease in condenser vacuum or a decrease 5 in steam pressure, the circuit through the relay coil 86 is broken whereby the switch arm 87 is moved out of engagement with the contact 88 to stop the further operation of the circulating pump 12.

10 Summarizing the operation of the complete control system, the boiler steam pressure may or may not be maintained at a predetermined minimum value depending upon whether or not the pressure switch 50 is used. Upon a call for cooling 15 by the condition responsive device 46, the boiler 25 is placed in operation to generate steam subject to the operation of the high limit control 55, the low water cut-off control 68 and the evaporator temperature controller 80. In this manner, the boiler 25 is placed in operation upon a 20 demand for cooling and this operation is safeguarded with respect to abnormally high steam pressures and low water level and the boiler is also prevented from operating in case the evaporator temperature should become so low as to cause freezing of the refrigerating mechanism. When the boiler pressure rises to a predetermined 25 value of 9 lbs., the pressure responsive device 60 places the secondary ejectors 21 and 22 in operation, places the vacuum pump 33 in operation, and also causes circulation of condensing water 30 through primary and secondary condensers 18 and 20 by either opening the valve 40 or by placing the circulating pump, not shown, in operation. Therefore, at some intermediate steam pressure, the refrigerating mechanism is placed in condition for operation and in case the steam pressure drops below this intermediate value, the 35 secondary ejectors 21 and 22, the vacuum pump 33 and the condensing water circulating means are 40 rendered inoperative. When the boiler pressure increases to a higher value of 12 lbs., and when the vacuum within the condensers 18 and 20 is brought to a predetermined minimum value of 16 45 inches of mercury, the primary steam valve 26 is opened to allow operation of the primary ejector 17 to create a vacuum in the evaporator 10 whereby the cooling process may be carried out and to increase the vacuum in the condenser 50 above the predetermined minimum value of 16 inches of mercury. The circulating pump 12 for 55 circulating the chilled water is placed in operation simultaneously with the placing in operation of the primary ejector 17 whereby the chilled water is immediately circulated to the cooling coil 13 located in the conditioning unit 14. In case the steam pressure should drop below 12 lbs., and/or the vacuum should decrease below 16 60 inches of mercury, the primary ejector 17 and the chilled water circulating pump 12 will be rendered inoperative. When the thermostat 46 is satisfied so as to no longer demand cooling, the 65 firing means for the boiler 25 is stopped and the boiler pressure decreases causing shutting down 70 of the refrigerating mechanism.

75 Although for purposes of illustration, we have used definite pressure and temperature values, other pressure and temperature values may be used and such is within the contemplation of this invention. By reason of the above control system,

an accurate and safe control of a steam jet ejector type refrigerating mechanism is obtained. Although we have disclosed one form of our invention for purposes of illustration, other forms thereof may become apparent to those skilled in the art and consequently, this invention is to be limited only by the scope of the appended claims and prior art.

We claim as our invention:

1. In a steam jet ejector cooling device including primary and secondary ejectors, a boiler for supplying steam to said ejectors, a primary valve in control of the flow of steam to the primary ejector and a secondary valve in control of the supply of steam to the secondary ejector, the combination of means responsive to a demand for operation of the cooling device and operative to place said boiler in operation, and pressure responsive means responsive to boiler pressure operative to open the secondary valve at a first boiler pressure, to open the primary valve at a higher second boiler pressure, and to render the boiler inactive at a higher third boiler pressure.

2. In a cooling system having a cooling coil for cooling a space, a steam operated cooling mechanism including a condenser, an evaporator and primary and secondary ejectors for supplying chilled fluid to the cooling coil, the combination of means in control of the circulation of chilled fluid to the cooling coil, a condensate pump for the cooling mechanism, a valve in control of the condenser water for the cooling mechanism, a boiler for supplying steam to said ejectors, a primary valve in control of the flow of steam to the primary ejector, a secondary valve in control of the supply of steam for the secondary ejector, a thermostat responsive to the temperature of the space operative to place said boiler in operation upon a demand for cooling, and means responsive to boiler pressure to open the secondary valve and condenser water valve and to operate the condensate pump at a low boiler pressure, to open the primary valve and operate the circulation controlling means at an intermediate boiler pressure, and to render the boiler inoperative at a high boiler pressure.

3. In a cooling system having a cooling coil for cooling a space, a steam operated cooling means including a condenser, an evaporator and primary and secondary ejectors for supplying chilled fluid to the cooling coil, the combination of means in control of the circulation of chilled fluid to the cooling coil, a condensate pump for the cooling means, a valve in control of the condenser water for the cooling means, a boiler for supplying steam to said ejectors, a primary valve in control of the flow of steam to the primary ejector, a secondary valve in control of the supply of steam to the secondary ejector, a thermostat responsive to the temperature of the space operative to place said boiler in operation upon a demand for cooling, and means responsive to boiler pressure to open the secondary valve and condenser water valve and to operate the condensate pump at a low boiler pressure, and to open the primary valve and operate the circulation controlling means at a higher boiler pressure.

4. In a conditioning system having an evaporator, an ejector therefor, a condenser, and a boiler, the combination of means responsive to a condition to be controlled and to the evaporator temperature for controlling the operation of said boiler, and means responsive to boiler pressure for controlling the operation of the ejector.

5. In a cooling system having an evaporator, 75

- an ejector therefor, a condenser and a boiler, the combination of means responsive to evaporator temperature and boiler pressure for controlling the operation of said boiler and means responsive to boiler pressure and condenser vacuum for controlling the ejector.
6. In a cooling system having an evaporator, an ejector therefor, a condenser and a boiler, the combination of means responsive to the temperature to be controlled, evaporator temperature and boiler pressure for controlling the operation of said boiler and means responsive to boiler pressure and condenser vacuum for controlling the ejector.
- 15 7. In a conditioning system having an evaporator, an ejector therefor, a condenser and a boiler, the combination of means for controlling the flow of the cooling medium, means for controlling the flow of the condenser fluid, means for controlling the operation of the ejector, means for controlling the operation of the boiler, means responsive to evaporator temperature and boiler pressure for controlling said boiler control means and said condenser fluid controlling means, and 20 means responsive to condenser vacuum and boiler pressure for controlling said ejector controlling means and said cooling medium flow control means.
- 25 8. In a steam jet ejector cooling device including primary and secondary ejectors, a boiler for supplying steam to said ejectors, a primary valve in control of the flow of steam to the primary ejector and a secondary valve in control of the supply of steam to the secondary ejector, the combination of means responsive to a demand for operation of the cooling device and operative to place said boiler in operation, and pressure responsive means responsive to boiler pressure operative to open the secondary valve at a first 30 boiler pressure, and to open the primary valve at a higher second boiler pressure.
- 30 9. A control system for a boiler which supplies steam to a steam jet refrigerating apparatus, comprising in combination means for controlling the supply of fuel to the boiler and means responsive to the evaporator temperature of the steam jet refrigerating apparatus and to a demand for cooling for controlling said fuel controlling means.
- 45 10. A control system for a boiler which supplies steam to a steam jet refrigerating apparatus, comprising in combination means for controlling the supply of fuel to the boiler and means responsive to the evaporator temperature of the steam jet refrigerating apparatus, to a demand for cooling and to boiler pressure for controlling said fuel controlling means.
- 50 11. In a steam operated cooling mechanism including primary and secondary ejectors, a boiler for supplying steam to said ejectors, a primary valve in control of the flow of steam to the primary ejector and a secondary valve in control of the supply of steam to the secondary ejector, the combination of means responsive to the establishment of a condition of low boiler pressure to cause opening of said secondary valve, means responsive to the establishment of an intermediate boiler pressure and a predetermined vacuum in a portion of the cooling mechanism to cause opening of said primary valve, and means responsive to the attainment of a high predetermined boiler pressure to render the boiler inactive.
- 55 12. In a steam operated cooling mechanism including primary and secondary ejectors, a boiler for supplying steam to said ejectors, a primary valve in control of the flow of steam to the primary ejector and a secondary valve in control of the supply of steam to the secondary ejector, the combination of means responsive to the establishment of a condition of low boiler pressure to cause opening of said secondary valve, and means responsive to the establishment of an intermediate boiler pressure and a predetermined vacuum in a portion of the cooling mechanism to cause opening of said primary valve.
- 60 13. In a conditioning system having an evaporator, primary ejector means associated with the evaporator, a primary condenser connected to said ejector means, a secondary condenser and secondary ejector means arranged to exhaust vapors from the primary condenser and discharge the same into said secondary condenser and to exhaust non-condensable vapors from said secondary condenser, and a source of steam connected to said ejector means, the combination of means responsive to the pressure of said source of steam for controlling the operation of said secondary ejector means and means responsive to the pressure of said source of steam and the vacuum in said secondary condenser for controlling said primary ejector means.
- 65 14. In a conditioning system having an evaporator, primary ejector means associated with the evaporator, a primary condenser connected to said ejector means, a secondary condenser and secondary ejector means arranged to exhaust vapors from the primary condenser and discharge the same into said secondary condenser and to exhaust non-condensable vapors from said secondary condenser, and a boiler, the combination of means responsive to a condition to be controlled and the evaporator temperature for controlling the operation of said boiler, means responsive to boiler pressure for controlling the operation of said secondary ejector means, and means responsive to the vacuum in one of said condensers and boiler pressure for controlling the operation of the primary ejector means.
